RAIL CHAIR

Robert Hill, Oakville, Ontario, Canada

Application August 7, 1931, Serial No. 555,773
In Canada July 7, 1931

14 Claims. (Cl. 238—304)

This invention relates to rail chairs generally and more particularly to a device of this description in which the use of clamping bolts for the rail are dispensed with.

10 The objects of the invention are to provide a durably constructed device of this character with a minimum number of parts which can be most economically manufactured and which will more efficiently perform the functions required of it.

Another object is to provide a rail chair in the manufacture of which time, labour and expense is reduced to a minimum.

In carrying into effect the foregoing and other objects hereinafter more fully dealt with the novel features of the device include a base plate adapted to be secured on a railroad tie or the like, rolled to form channelled ridges or walls thereon and provide therebetween a seat for the base of a rail, the walls being formed with bent portions relative to the channels and an opening through said portions and the base plate, a clamping member adapted for engagement with said opening while clamping the rail and resting upon the walls, and a locking pin carried by the walls for engagement with the clamping member whereby the latter is locked in position and whereby on the bent portions being clinched, the locking pin is retained in locking position.

20 The invention will be best understood by reference to the following description when taken in connection with the accompanying illustration of one specific embodiment thereof while the scope of the invention will be more particularly pointed out in the claims.

Referring now to the drawing and to the embodiment therein disclosed for illustrative purposes and in which like numerals of reference indicate corresponding parts in each figure.

25 Fig. 1 is an end view partly in section of the device with a rail seated and clamped therein.

Fig. 2 is a plan view.

Fig. 3 is a detail of the clamping member or keeper.

30 Fig. 4 is a detail of the locking pin.

Fig. 5 is a modified form of the locking pin.

Fig. 6 is a modified form of the clamping member.

35 Referring now more particularly to the drawing, A, designates the base plate adapted by means of the holes 10, therein to be secured in well known manner to a railroad tie or the like. This plate is rolled from a bloom forming the transverse ridges 11, and 12, providing a space

or seat 13, therebetween for the base 14, of a rail B. In short, a chair for the rail.

Instead of as heretofore in devices of this description in which bolts or the like were used to clamp the rail in the chair, I provide channels 40 17, formed in the ridges or walls 11, and 12, and intermediately separated as at 18, to register with a hole 19, in the base plate hereinafter more fully referred to. The channels 17, are also intermediately bent as at 21, and 22, on each side of the hole 19, to form lip portions 23. A clamping member 24, as here shown substantially T-shaped, fits into the opening 19, and in the stem 25, thereof is provided an opening or hole 26, while the inner surface of the top conforms as at 28, to the top contour of the rail base 29, and is adapted to fit loosely relative thereto, providing sufficient space therebetween to eliminate undue stress on the locking means for said member 45 hereinafter more fully referred to. Another feature and a very important one in connection with this clamping or keeper member 24, is that it is reversible relative to the rail and the walls or ridges 11, and 12, of the plate.

For locking the member 24, a key or pin 31, is 50 provided which is slipped in through the channels 17, in the ridges 11, and 12, and through the hole 26, in the member 24, while to retain this pin in locking position, the ends of the lips 23, are clinched or bent down as at 32, in any suitable 55 manner when the locking pin being of substantially the same length as these lipped or bent portions of the ridges or walls, it is thereby securely retained in position. To remove the pin, when replacing a rail, it is only necessary to force 60 it out in any well known manner. It should here be noted that this locking pin may be bent at one end to form a driving head and intermediately curved to provide spring action in the clamping member and the bent walls. Furthermore, the fact that the locking pin loosely engages with the clamping member and rigidly engages with the walls or sides of the chair, permits play of the former to take up stress on the locking pin while providing for any wave motion 65 of the members involved.

In operation. The rail having been placed in the seat 13, between the ridges or walls 11, and 12, on the base plate, and the clamping or keeper member placed in the hole 19, and the lip portions 70 having already been clinched at one end as at 23, the locking pin 31, is inserted through the hole 26, the other ends of the lip or bent portions are then clinched, completing the operation.

The simplicity and effectiveness of this con- 75

struction and the increased speed at which a rail can be placed in operative and secure position are results that could not be achieved with means heretofore or at present in use.

- 5 It will be seen from the foregoing that applicant has developed a device of the character disclosed in which flexibility is provided for, as well as durability and economy in construction, thereby ensuring smooth and safe travel thereover.
- 10 Various forms of the apparatus described will suggest themselves to those skilled in the art; it is, therefore, not intended that the present application should be limited to any particular form of construction; modifications may be made
- 15 in the apparatus above described within the scope of the claims, without departing from the spirit or scope thereof.

What I claim for my invention is:

1. A rail chair comprising a plate formed with spaced transverse ridges adapted to hold therebetween a rail, clamping members co-operative with the plate and arranged to extend into the ridges and the plate, securing means for holding the clamping members in flexible relationship with the rail, and means formed in the top surfaces of the ridges for holding the securing means.
2. A rail chair comprising a plate formed with spaced transverse walls, formed with recesses in the top surfaces thereof, a clamping member adapted for engagement with the rail, the walls and said plate formed with an opening therethrough, a detachable pin located in the recesses in the top of the walls for flexibly locking the clamping member in position.
3. A rail chair comprising a base-plate formed with spaced parallel walls having recesses in the top thereof adapted to house securing means, clamping members formed for simultaneous engagement with a rail between the walls, the base plate and the walls, locking means, for flexibly locking the clamping members, located in said recesses and adapted to maintain the clamping members in yieldable engagement with the rail.
4. In a rail chair, a base plate formed with spaced transverse ridges and stamped to form channels in the ridges and an opening through the ridges into the plate, rail clamping members adapted for simultaneous engagement with the rail, a ridge and the base plate, and means for locking the clamping members, cooperating with the channelled ridges and the clamping members.
5. In a rail chair, a plate formed with walls adapted to carry locking means, a substantially T-shaped clamping member for simultaneous engagement with a rail, a wall and said plate, and means in the clamping member co-operating with the walls to receive the locking means to lock the clamping member and retain such means locked.
6. In a rail chair, a base plate provided with bolt openings and formed with spaced transverse walls to provide a seat therebetween for the base of a rail and to engage with the sides of said base, said walls being channelled and having intermediate thereof bent sections, and an opening through said section, an apertured clamping member adapted for simultaneous engagement

with the rail base, the ridges and the base plate, a locking pin engaging the ridges and the clamping member and adapted upon said sections being bent, to be retained in locking position.

7. In a rail chair, a base plate with spaced transverse walls formed with bent sections, a locking pin for detachable engagement with said walls, whereby on said sections being clinched, the pin is retained in the walls, and means through the walls and the base plate for the reception of a clamping member adapted to simultaneously clamp with the rail and engage with the walls and the locking key therein.

8. In a device of the character described, the combination with a tie plate adapted to form a seat for a rail, of a substantially T-shaped reversible keeper or clamping member for the rail associated with the seat, and spring actuated locking means associated with the seat and said member adapted to impart a flexible spring effect thereto.

9. In a device of the character described, the combination with a base plate formed with bent side walls adapted to provide therebetween a seat for a rail, of a clamping member or keeper, and locking means associated with said member and the aforementioned walls adapted to provide spring action in the clamping member and said walls.

10. In a rail chair and in combination, a base formed with spaced parallel walls provided in the top with recesses adapted to carry and retain flexible locking means, keeper members co-operative with the walls and said base, flexible locking means for the keeper members in the walls to maintain said members in spring-actuated flexible engagement with a rail between the walls, to permit free wave motion of the rail under traffic pressure.

11. In a rail chair and in combination, a base plate formed with spaced parallel walls for engagement with a rail seated therebetween, said walls having recesses therein, keeper members for opposite sides of the rail, co-operative with the walls and the base plate, detachable locking means for the keeper members positioned in the walls above the top surface of the base plate.

12. In a rail chair and in combination, a base plate formed with spaced parallel walls to seat a rail therebetween, said walls being channeled in the top surface thereof, clamping members associated with the walls and the base plate, and locking means for said members co-operative with the wall channels and with the clamping members.

13. The invention according to claim 11, in which the keeper member is folded on itself to provide a spring effect.

14. A rail chair comprising a base formed with parallel spaced walls on the top surface thereof at substantially right angles to said surface, spring-actuated rail-retaining members cooperative and removable relative to the base and to said walls, and resilient locking means in the walls for said members, to provide flexible retaining means for a rail seated between the walls.

ROBERT HILL.
